UNITED STATES PATENT OFFICE

ALFORD C. BARROWS AND GEORGE W. LANGFORD, OF ANN ARBOR, MICHIGAN, AS-
SIGNORS TO ECONOMY BALER COMPANY, OF ANN ARBOR, MICHIGAN, A CORPORA-
TION OF MICHIGAN

BALING PRESS

Application filed July 18, 1927. Serial No. 206,647.

The invention relates to baling presses of that type having longitudinally extending slots in its end walls through which the bar of the compressing plunger extends. The 5 invention has for its main object the provision of means for closing the slots to prevent the material within the baling chamber from being forced therethrough. The invention has for another object the provision 10 of slot closure means, which is movable upon movement of the compressing plunger to allow movement of the compressing plunger bar. With these as well as other objects in view, the invention resides in the novel features of construction and combinations and arrangements of parts as more fully herein- 15 after set forth.

In the drawings:—

Figure 1 is a diagrammatic end elevation 20 of a baling press, embodying our invention;

Figures 2 and 3 are cross sections, respectively, on the lines 2—2 and 3—3 of Figure 1;

Figures 4, 5 and 7 are views similar to Figure 1, showing modified constructions;

Figure 6 is a cross section on the line 6—6 25 of Figure 5;

Figure 8 is a cross section on the line 8—8 of Figure 7;

Figure 9 is a view similar to Figure 2, 30 showing a modified construction;

Figure 10 is an end elevation of a portion thereof.

As shown in Figures 1, 2 and 3, 1 is the baling chamber of the baling press, which is 35 specifically formed by the doors 2 pivotally mounted upon the stationary end wall 3, the doors having the transverse portions 4 at their free ends together forming the opposite end wall of the baling chamber. The stationary end wall 3 has the central longitudinally extending slot 5, while the portions 4 of the doors terminate short of each other to form the central longitudinally extending slot 6 in the opposite end wall. 7 is the compressing 40 plunger, which is movable longitudinally within the baling chamber 1 and in the present instance is movable downwardly toward the stationary platen to compress the material within the baling chamber. This plunger 45 is mounted upon the plunger bar 8, which 50

extends through the slots 5 and 6 of the baling chamber and is actuated by suitable means such as the chain 9 at each end of the baling chamber and outside the same and extending over the wheels 10 and 11, respectively, at the upper and lower ends of the baling chamber, the latter wheel being preferably power driven. The arrangement is such that upon upward movement of the plunger it will be carried upwardly from the baling chamber and tilted to permit the material to be compressed to be thrown into the baling chamber through its upper end. 55

For the purpose of preventing the material within the baling chamber from passing out through the slots 5 and 6 or being forced outwardly through these slots during the compression movement of the compressing plunger, we have provided the flexible member 12 which extends longitudinally within 60 each of the slots and around the wheels 13 and 14, respectively, at the upper and lower ends of the baling chamber. This flexible connection is preferably a cable of a diameter substantially equal to the width of either slot 65 and having its ends connected to the plunger bar 8 so that it moves with the plunger bar and will not interfere with the movement of the latter in the slots. 70

In the modification shown in Figure 4, 80 the baling press is of the upstroke type, in which the compressing plunger 15 is movable upwardly toward the platen to compress the material within the baling chamber. The arrangement of the compressing plunger bar 85 and actuating means is the same in both instances. However, in this baling press the means for closing each slot in the end of the baling chamber comprises the flexible member 16, such as a cable, which extends longitudinally within each slot above the compressing plunger bar. One end of this cable is connected to the compressing plunger bar, while the other end is connected to the counterweight 17, an intermediate portion 90 passing over the wheel 18. With this arrangement, the slot closure means also moves with the compressing plunger bar, but during the compression movement of the compressing plunger the slot closure means is 95 100

actuated by a counterweight which should be sufficiently heavy to maintain the slot closure means taut.

Figures 5 and 6 disclose another modification of baling press which, as specifically shown, has the same general arrangement of parts as the baling press of Figures 1, 2 and 3, with the exception that the slot closure means is different. 19 is a slot closure bar 10 extending longitudinally of the baling chamber at each of its ends and adapted to register with a longitudinally extending slot of the baling chamber. This bar is located adjacent the outer edge of the slot and is normally held in registration with the slot by means of the levers 20 and 21, which have their inner ends pivotally connected respectively to the upper and lower ends of the closure bar and their outer ends connected to 15 the coil springs 22, these levers being pivotally mounted intermediate their ends upon the end walls of the baling chamber. The upper inner edge of each closure bar 19 is cammed as at 23 for engagement with the 20 compressing plunger bar when lowered, so that this latter bar will gradually force the closure bar out of registration with the slot, at which time the closure bar pivots about the lower lever 21. The closure bar also has 25 its lower inner edge cammed for engagement with the compressing plunger bar, if used in an upstroke type baling press.

In the modification shown in Figures 7 and 8, the slot closure means is still different, 30 it including the series of pivotally connected flat links 24, which normally register with each slot at its outer edge, each link being held in this position as by means of the coil spring 25. The links extend upwardly above 35 the baling chamber so that the uppermost link clears the compressing plunger bar when tilted, so that when the compressing plunger is lowered its bar comes successively into engagement with the links to laterally force the 40 same out of registration with the slot.

Figures 9 and 10 illustrate another modification of baling press which, as specifically shown, is of the upstroke type having the compressing plunger 26 movable upwardly 45 within the baling chamber 27 and toward the stationary platen to compress the material within this baling chamber. The plunger bar of the compressing plunger extends through the vertically extending slots in the 50 opposite end walls of the baling chamber in the same manner as those previously described and its ends are connected to chains 27 by means of the clevises 28. For preventing material within the baling chamber from 55 passing out through the slots of the baling chamber or being forced outwardly through these slots during the compressing movement of the compressing plunger, there is 60 the flexible connection 29, preferably a cable, for each slot. The upper end of each cable

is secured to the frame of the baling press in a manner to extend longitudinally within each slot and close the same downwardly to the plunger bar. The cable then passes around the sheaves 31 and 32, which are connected to the plunger bar and are located thereabove, the sheave 32 preferably extending between the bifurcations of the clevis 28. The cable then extends downwardly to near the bottom of the baling press frame, to which it is connected by means of the coil spring 33, which is sufficiently strong to maintain the cable taut at all times. The sheave 31 is located to extend within the slot at that end of the baling chamber and as a result the portion of the cable on the compressing side of the compressing plunger or in the present instance above the compressing plunger is always located in the slot.

What we claim as our invention is:

1. In a baling press, a baling chamber having a slot in one of its walls, a compressing plunger movable within said chamber, a bar connected to said plunger and extending through said slot, and a flexible member connected to said bar and extending longitudinally within said slot and having a width substantially equal to the width of the latter.

2. In a baling press, a baling chamber having a slot in one of its walls, a compressing plunger movable within said chamber, a bar connected to said plunger and extending through said slot and a flexible member extending longitudinally of said baling chamber and having its portion on the compressing side of said compressing plunger extending longitudinally within said slot.

3. In a baling press, a baling chamber having a slot in one of its walls, a compressing plunger movable within said chamber, a bar connected to said plunger and extending through said slot, a flexible member, resilient means for maintaining said flexible member taut, and means upon said bar for locating the portion of said flexible member on the compressing side of said compressing plunger within the portion of the slot on the compressing side.

4. In a baling press, a baling chamber having a slot in one of its walls, a compressing plunger movable within said chamber, a bar connected to said plunger and extending through said slot and a cable extending longitudinally of said baling chamber and having its end on the compressing side of said compressing plunger extending within said slot, and sheaves upon said bar and around which said cable runs, said sheaves being located on the compressing side of said compressing plunger and one sheave being positioned to locate the portion of said cable in engagement therewith within said slot.

5. In a baling press, a baling chamber having a slot in one of its walls, a compressing plunger movable within said chamber, a bar

connected to said plunger and extending through said slot, a flexible member connected to said bar for actuating the plunger, and a second flexible member also connected to said bar and having portions extending longitudinally within the slot for sealing the latter.

5 6. In a baling press, a baling chamber having a slot in one of its walls, a compressing plunger movable within said chamber, a bar connected to said plunger and extending through said slot, and means for sealing said slot including a member having portions extending longitudinally within the slot and movable out of the latter by said bar.

10 7. In a baling press, a baling chamber having a slot in one of its walls, a compressing plunger movable within said chamber, a bar connected to said plunger and extending through said slot, and a flexible closure member for said slot movable laterally out of registration with the latter.

15 8. In a baling press, a baling chamber having a slot in one of its walls, a compressing plunger movable within said chamber, and means registering with said slot for sealing the same including, a flexible member of a width to substantially close the slot and having portions movable successively out of registration with the slot upon movement of the plunger.

20 In testimony whereof we affix our signatures.
